Pearson & Neal,

Washing Machine,

N° 18,407.

Patented Oct. 13, 1857.

UNITED STATES PATENT OFFICE.

BENJN. H. PEARSON AND DANL. B. NEAL, OF MOUNT GILEAD, OHIO.

WASHING-MACHINE.

Specification of Letters Patent No. 18,407, dated October 13, 1857.

To all whom it may concern:

Be it known that we, BENJAMIN H. PEARSON and DANIEL B. NEAL, of Mount Gilead, in the State of Ohio, have invented certain new and useful Improvements in Washing-Machines; and we do hereby declare that the following is a full, clear, and exact description of the same, reference being had to the accompanying drawings and to the 10 letters of reference marked thereon.

The nature of our invention consists in the arrangement and operation of certain devices for washing clothes, the peculiarities of which will be hereinafter disclosed.

15 In order that those skilled in the art may use and manufacture our invention we will proceed to give a description of its construction and operation.

In the accompanying drawings which 20 make a part of this specification Figure 1 is a plan view of the machine. Fig. 2 is a section taken in the line $\alpha\alpha$ Fig. 1. Fig. 3 is a view of a head and rubbers.

In Fig. 1, A represents the circular head, 25 to which the rubbers are attached. O is the tub or vessel in which the heads are operated. (E) is a cross plate stationed on the top of the machine by means of pins (a a) and serves to keep shaft F in proper 30 position and also serves to support the levers (B, B'). B and B' are levers, B, being attached to shaft F and operating it, B' being attached to hollow shaft, G, and operating it in a different direction. C and 35 C', are levers attached respectively to levers B, B', at one end, their other ends being attached to the connecting cross piece (c). This cross piece c, it will be seen is attached to lever D, which lever operates C C', B, 40 B', shafts F, and G, and consequently the two heads of the machine in different directions; H, is a slotted guide for the lever D.

In Fig. 2, O is the tub or vessel. A and A' are the two heads of the machine. F, is 45 a shaft resting on the bottom of the machine and to which is attached firmly the head, A'. G, is a bottom shaft through which shaft F passes and to which head A is attached as seen. B is a lever attached 50 to shaft F, and B' is a lever attached to shaft G, both connecting as seen in Fig. 1 with lever D. (e e) are catches on lever D,

for attaching cross piece (c) seen in Fig. 2 to said lever. (d) is a hook or ring attaching lever D, at its lower extremity to the 55 machine. c and b form a spring catch for the lever extremity of shaft F, and serve to keep it in position.

Fig. 3 is simply a head of the machine showing the rubbers. Each one of the heads 60 A and A' are provided with these rubbers, which may be made semicircular or any convenient and desirable form.

In the operation of this machine the cross piece (c) being detached from lever D, 65 we raise cross piece E to which is attached the levers, C C', and B, B', shaft G, and the upper head A. This being done we proceed to place the clothes to be washed between the two heads A and A'. We then 70 replace the cross piece E, attach the lever D, and proceed to operate it backward and forward. Lever D it will be seen, operating upon C, C' and B, B', give the two heads of the machine motion in different 75 directions from each other. The clothes are thus rubbed between the two heads without the constant tendency to move around with the head in the machine. The heads thus moving in different directions tend to turn 80 the clothes over and over while being rubbed and being kept in constant motion of this kind the dirt is easily removed and the clothes cleansed. The rubbing heads of the machine may be placed close together so that 85 small articles of clothing may be washed, but it will be perceived that in washing larger articles or a number at a time the head A will be raised up by the clothes and will press on them with its own and the 90 weight of the levers B, B' and C C', or if these are not sufficient an additional weight may be used and applied to head A. The cross piece E raises up and down on the pins (a a) (the levers working equally well 95 in any position it assumes) and thus allows of the adjustability of the head A to suit the volume of clothes.

We do not claim any of the members of this machine to be new, for they may all be 100 found in every day use, but we are not aware that the peculiar arrangement and operation of the devices which we have employed in our invention have ever before

been used in this connection and for this purpose.

Having thus fully described our invention what we do claim and desire to secure by Letters Patent is—

The heads or disks A A', in combination with the adjustable cross piece E, construct-

ed, and operating in the manner and for the purpose set forth.

BENJAMIN H. PEARSON.
DANIEL B. NEAL.
